UNITED STATES PATENT OFFICE.

FRANK NOVAK, OF CHICAGO, ILLINOIS.

DESIGN FOR A BOTTLE.

45,646.

Specification for Design.

Patented Apr. 21, 1914.

Application filed March 4, 1914. Serial No. 822,532. Term of patent 14 years.

To all whom it may concern:

Be it known that I, FRANK NOVAK, a citizen of the United States, residing at Chicago, in the county of Cook and State of Illinois, have invented a new, original, and ornamental Design for Bottles, of which the following is a specification, reference being had to the accompanying drawing, forming a part thereof.

The figure is a perspective view of a bottle, showing my new design.

I claim:

The ornamental design for a bottle, as shown.

FRANK NOVAK.

Witnesses:

JOSEF KOZA,
JOSEPH A. CERNY.
